UNITED STATES PATENT OFFICE.

RAY MERTZ, OF AKRON, OHIO, ASSIGNOR TO THE MILLER RUBBER COMPANY, OF AKRON, OHIO, A CORPORATION OF OHIO.

REENFORCED HORN.

Application filed August 11, 1923. Serial No. 656,891.

To all whom it may concern:

Be it known that I, RAY MERTZ, a citizen of the United States, and resident of Akron, in the county of Summit and State of Ohio, have invented certain new and useful Improvements in Reenforced Horns, of which the following is a specification.

My present invention relates to improvements in megaphones, and aims to produce a horn which will have the desired characteristics as a sound amplifier, which may be manufactured at an extremely low cost, and which will be strong and durable in use.

Heretofore sound amplifiers have been made of rubber compound containing a blowing ingredient, as disclosed in an application filed in the United States Patent Office on the 18th day of December, 1922, Serial No. 607,610, said application and the present one being owned by one and the same assignee.

It has been found that by varying the hardness of the rubber composing the horn, the characteristics thereof as a sound amplifier can be varied or modified, and that for many purposes a relatively soft compound is more desirable, though by the word "soft" I do not wish to be understood as meaning what is known to the trade as "soft rubber," but on the contrary, the horn is composed of hard rubber though of a softer cure than is customary. It has been found that such softer horns are liable to sag in warm atmospheres so as to change their shape and also danger of such change of shape in shipping.

The present invention aims to remove this objection in a manner which will not impair the sound producing characteristics of the horn and to this end the invention comprises the novel construction hereinafter described, and defined by the appended claims.

My invention is illustrated in the accompanying drawings, in which:

Figure 1 is a side elevation of such a horn or megaphone.

Fig. 2 is a front elevation, partly broken away.

Fig. 3 is an enlarged sectional detail.

Referring by reference characters to this drawing, the numeral 1 designates the horn proper which, as stated, is made of hard rub-

ber compound containing a blowing ingredient, which, during vulcanization, will be gasified and produce throughout the body of the rubber a multiplicity of cells. In order to reinforce the horn or amplifier to prevent distortion, I embody therein metal reinforcements. I have found, however, that to secure the best results and preserve the sound characteristics or advantages of the rubber horn, a certain specific arrangement of the reinforcements is desired. My preferred form of reinforcement comprises an annular reinforcement for the flared mouth of the amplifier, which is in the shape of a ring 2, and upper and lower reinforcements extending lengthwise of the horn, indicated at 3 and 3^a. These lengthwise reinforcements are preferably made in the form of flat 60 braided wire, as shown, which wire is preferably impregnated with a rubber compound before being embodied in the horn. By the use of braided or woven wire in this manner, the reinforcement is prevented from being forced to the surface of the horn in molding. I have found that if a solid ring reinforcement is used at the mouth of the horn, it is liable to be forced to the surface in the molding process, due to differences in expansion, 65 and I therefore, use a split ring with the ends telescoped into a short piece of metal tubing, as indicated at 2^a. The longitudinal reinforcements 3 and 3^a, are not connected with the ring in any way, but simply overlie 70 the same so as to avoid any pull upon the ring from the longitudinal reinforcements due to temperature changes.

A horn reenforced as above described, leaves the greater part of the material self-supporting, while the single ring at the mouth of the horn, which is the most inactive part, but which is most liable to damage in rough handling, effectively reinforces it and braces it against distortion. The lengthwise 90 supports of braided or woven wire, serve effectively to prevent the horn from sagging, while at the same time, they do not interfere with the sound characteristics.

Having thus described my invention, what I claim is:

1. A sound amplifier or megaphone composed of vulcanized rubber compound having a metallic reinforcing ring embedded

therein adjacent the mouth of the horn, said ring having its ends telescopically connected.

2. A sound amplifier or megaphone composed of vulcanized hard rubber compound having lengthwise disposed reinforcing elements of braided or woven wire.

3. A sound amplifier or megaphone composed of vulcanized rubber compound hav-

ing an annular metallic reinforcement in the mouth thereof, and lengthwise disposed metallic reinforcements embedded in the material thereof, and free from connection with the said annular reinforcement. ¹⁰

In testimony whereof, I affix my signature.

RAY MERTZ.
